METHOD OF MAKING HINGE MEMBERS

Seth B. Atwood, Rockford, Ill.

Application August 31, 1940, Serial No. 354,934

4 Claims. (Cl. 29—11)

This invention relates to hinges and is particularly concerned with an improved method of making hinge members.

The improvements of my invention are applied to a hinge member of varying width and thickness, wider and thinner in the attaching portion and thicker in the pintle end portion and of varying width and thickness at intermediate points, and made from bar stock which for economy is of a certain reduced width and thickness, the hinge members being produced by passing the bar between rolls, one with a plain periphery and the other with a cam-shaped periphery conformed to give the hinge blanks certain desired thicknesses at various points along the length thereof, a number of blanks being thus formed at a time in each strip and the blanks being cut from the strip after rolling. This method, therefore, enables the production of hinge blanks in which the grain runs lengthwise of the piece to give greater strength and also facilitate production by permitting bending without danger of weakening the piece, while also making it possible to straighten a bent hinge without danger of breakage.

The principal object of my invention is to provide hinge blanks in the manner described, which at some point subsequent to the initial rolling and forming are subjected to heavy pressure edgewise and endwise, one or both, in a coin press so as to give the pintle end portion the desired increased thickness so that when a pintle hole of conventional size is drilled through this portion there will be ample wall thickness around the hole for adequate strength. This method, therefore, enables use of bar stock of much thinner section than would otherwise be required while still affording adequate strength, and means an appreciable saving in cost. When the pressure is applied edgewise, there is an added advantage from the standpoint that harder and smoother bearing surfaces are produced on the two edges adjacent the upper and lower ends of the pintle hole to give increased durability. The compression of the pintle end portion also obviously makes for closer grained metal throughout this portion, and the pintle hole is therefore a much more durable bearing than would otherwise be provided, the closer grain of the metal being also advantageous generally from the standpoint of greater strength and rigidity in the most important pintle end portion.

The invention is illustrated in the accompanying drawing, in which—

Figure 1 is a perspective view of a portion of **55** Figure 1 is a perspective view of a portion of a hinge member.

the kind of bar stock used in the production of the present hinge members;

Fig. 2 is a view of the same portion of bar stock as it appears after the initial rolling and forming operation;

Fig. 3 is a side view on a slightly enlarged scale of a portion of one of the blanks cut from the bar shown in Fig. 2;

Fig. 4 is a section through the pintle end portion of the blank on the line 4—4 of Fig. 3;

Fig. 5 is a side view of the same blank after the pintle end portion has been coined in accordance with the present invention;

Fig. 6 is a section on the line 6—6 of Fig. 5, indicating the extent of increase in thickness resulting from the coining, and

Fig. 7 is a horizontal section through a portion of an automobile body and door illustrating a hinge of the type using the hinge members some of the steps in the production of which are illustrated in Figs. 1 to 6.

The same reference numerals are applied to corresponding parts throughout the views.

Referring briefly to Fig. 7 for an understanding of the hinge, **12** designates a portion of the body and **13** a portion of the door of an automobile. The hinge shown comprises an outer member **14** and an inner member **15** mounted on the body and door respectively. The outer member **14** is formed from sheet metal to a generally U-shaped cross-section so as to provide opposed substantially horizontal parallel walls, the lower one of which appears at **16** interconnected by a substantially vertical wall **17**. The horizontal walls have embossed portions **18** forming supports for the pintle **19** received in a bearing hole **20** provided therefor in the enlarged end portion **21** of the inner hinge member **15**. The walls **16** are also flanged outwardly as at **22** to provide attaching portions for bolting, riveting, or otherwise securing the outer hinge member **14** to the body pillar, a portion of which appears at **23**. A sheet metal face plate **24** suitably welded to the attaching portions **22** is cut away as at **25** to provide operating clearance for the inner hinge member **15**. The inner hinge member **15** has an offset portion **26** next to its attaching end portion **27** where it extends through the cut-out portion **25** of the plate **24**, whereby to provide operating clearances for the gooseneck portion **28** when the door closes. The gooseneck portion **28** is next to the offset portion **26**, and its radius is long enough so that the portion **30** clears the body pillar in the opening of the door. The pintle end portion **21** provided on the other half

of the gooseneck portion 28 is approximately at right angles to the attaching end portion 27, and the door 13 is accordingly free to swing through approximately 90° from closed to open position. Now, it can easily be seen by inspection of the inner hinge member 15 in Fig. 7 that it is desired to have the attaching portion 27 wide and of relatively thin section so as to provide proportionately broader surface engagement with the door to which it is secured. On the other hand, it is desirable to have the pintle end portion of narrower and thicker section, the thickened section permitting provision of a pintle bearing hole 20 of large enough diameter without reducing the wall thickness around the bearing hole to too great an extent. The section between the attaching portion 27 and the pintle end portion 21 is preferably of gradually increasing thickness outwardly and gradually increasing width inwardly, as indicated in Figs. 3 and 7.

Referring now to Figs. 1 to 4, 31 designates the steel bar stock from which B blanks are produced by rolling and forming between rollers in the manner illustrated in Tierney Patent 2,235,241, one of the rollers having a plain periphery so as to leave the blanks flat on one side, at indicated at 32 in Fig. 2, while the other roller is profiled or cam-shaped to conform to the shape of the other side 33 of the blanks to be produced, the rollers in one instance having cam surfaces for the formation of five blanks in each turn. The bar 31 has a cross-section approximately the same as the pintle end portion 21a of the blank, as shown in Figs. 2, 3, and 4, prior to the coining operation which produces the final thickness of the pintle end portion 21 of the inner hinge member 15, shown in Figs. 5, 6, and 7. The attaching end portion 27 of the blank, however, is much thinner and wider and is given that form by pressure between the rollers. The intermediate portions of the blanks between the ends 21a and 27 are of varying thickness and width, the blank decreasing in width but increasing in thickness gradually from the attaching end portion toward the pintle end portion 21a. The rolling and forming operation is done hot and the blanks are cut from the bar by shearing the same transversely at the points 34. In some instances the attaching end portions 27 will require milling off along the longitudinal edges to square them up and also get down to the desired width to fit the hinge seats on the automobile door. The extremities of the end portions 27 will ordinarily also require milling off square to bring the blank down to the desired length. Such trimming operations are simple and inexpensive. The blank is then bent transversely between dies to give the pintle end portion the desired angularity and lateral offset as shown in Fig. 7. The coining operation may precede or follow the bending operation, but preferably follows. In the coining operation pressure is applied to the longitudinal edges 35a and 36a and on the end 37a, as indicated by the arrows P in Fig. 5, to compress the pintle end portion to the reduced width and length indicated at 35, 36, and 37 in Figs. 5 and 6, the compression causing not only the flattening into true parallelism of the top and bottom surfaces 35 and 36 but also an appreciable increase in thickness throughout the pintle end portion, as most clearly appears from a comparison of Figs. 4 and 6. The edge portions of the blank are sheared by the coin press dies at the points 38 as the dies are moved toward each other under extremely heavy pres-

sure. The pintle hole 20 is then drilled through the compressed and thickened end portion 21 of the blank on a line directly at right angles to the parallel top and bottom bearing surfaces 35 and 36. As previously indicated, the pressure on the end 37a may be dispensed with, and preferably is, because sufficient increase in thickness can ordinarily be obtained by the edgewise compression alone.

The advantages derived by the coining operation are manifold. First of all, it enables use of bar stock 31 of less thickness than would otherwise be required and that, of course, means an appreciable saving in cost of production. The increased thickness results in increased strength at the point where the greatest strains are concentrated in the operation of the hinge. The compression edgewise illustrated in Fig. 5, in addition to giving the desired result of added wall thickness at 39 around the pintle hole 20, results in harder and smoother top and bottom bearing surfaces 35 and 36, while at the same time producing still closer grained metal around the bearing hole 20 so that the pintle bearing will have greatly increased resistance to wear. The initial rolling operation results in compacted grain throughout the length of the blank with resultant increased strength. The fact that the grain runs lengthwise is also very important because it permits bending without danger of weakening the piece, as well as making it possible to straighten a bent hinge without danger of breakage. The bending of the hinge member 15 to the final form shown in Fig. 7 results in "work hardness" and as a result the hinge member is stiffer and is not as apt to sag and take a set in bent form. A further important advantage in the initial roll evident from an inspection of Fig. 2 comes from the fact that the grain is not only compacted at the vicinity of the pintle hole 20, but the grain actually is curved around the pintle hole, thus greatly increasing the resistance to wear. The closer grain in the metal resulting from the edgewise and endwise compression, or edgewise compression alone, also makes for greatly increased strength and rigidity throughout the pintle end portion 21 of the inner hinge member 15. By the present method, therefore, the greatest strength is concentrated in that portion of the hinge member projecting from the body of the car, where the greatest strains occur under service conditions. This method of making the inner hinge members 15 requires no complication in the construction of the ultimate hinge assembly, because the horizontal top and bottom walls 16 of the outer hinge member 14 are spaced far enough apart to afford clearance for the gooseneck portion 28 which is of unreduced width, whereas the embossed portions 18 have their bearing surfaces 40 closer together and arranged either to contact the top and bottom bearing surfaces 35 and 36 directly with ordinary operating clearance or spacing washers may be provided between the hinge members at one or both ends of the pintle, as desired. In either event the smooth hardened bearing surfaces 35 and 36 on the inner hinge member 15 make for increased resistance to wear and proportionately increase the life of the hinge.

It is believed the foregoing description conveys a good understanding of the objects and advantages of my invention. The appended claims have been drawn to cover all legitimate modifications and adaptations.

I claim:

1. The method of making hinge members which consists in subjecting a bar of rectangular cross-section to a combination rolling and forming operation, whereby to form from a single bar a plurality of connected blank portions having the grain running lengthwise of all of said blank portions each blank portion as a result of the rolling operation having increased width and decreased thickness at one end, and intermediate thicknesses and widths intermediate the ends, and substantially the original width and thickness of the bar at the other end, then cutting the blanks from the bar, then compressing a short length of the last named end portion edge-wise so as to reduce the width of said portion but increase the thickness appreciably above that of the original bar, and finally drilling a pintle hole crosswise in said thickened end portion.

2. The method of making hinge members which consists in subjecting a bar of rectangular cross-section to a combination rolling and forming operation, whereby to form from a single bar a plurality of connected blank portions having the grain running lengthwise of all of said blank portions each blank portion as a result of the rolling operation having increased width and decreased thickness at one end, and intermediate thicknesses and widths intermediate the ends, and substantially the original width and thickness of the bar at the other end, then cutting the blanks from the bar, then compressing a short length of the last named end portion edge-wise and endwise so as to reduce the width of said portion but increase the thickness appreciably above that of the original bar, and finally drilling a pintle hole crosswise in said thickened end portion.

3. The method of making hinge members which consist in subjecting a bar of rectangular cross-section to a combination rolling and forming operation, whereby to form from a single bar a plurality of connected blank portions having the grain running lengthwise of all of said blank

portions each blank portion as a result of the rolling operation having increased width and decreased thickness at one end, and intermediate thicknesses and widths intermediate the ends, and substantially the original width and thickness of the bar at the other end, then cutting the blanks from the bar, then compressing a short length of the last named end portion edge-wise between substantially parallel dies so as to flatten the longitudinal edge portions contacted and thereby provide substantially parallel broad flat bearing surfaces on the hinge member hardened by reason of the local compacting of the grain, while at the same time decreasing the overall width of said end portion and increasing the overall thickness appreciably above that of the original bar, and finally drilling a pintle hole crosswise in said thickened end portion.

4. The method of making hinge members which consists in subjecting a bar of rectangular cross-section to a combination rolling and forming operation, whereby to form from a single bar a plurality of connected blank portions having the grain running lengthwise of all of said blank portions each blank portion as a result of the rolling operations having increased width and decreased thickness at one end, and intermediate thicknesses and widths intermediate the ends, and substantially the original width and thickness of the bar at the other end, then cutting the blanks from the bar, then compressing a short length of the last named end portion endwise and also compressing said portion edgewise between substantially parallel dies so as to flatten the longitudinal edge portions contacted and thereby provide substantially parallel broad flat bearing surfaces on the hinge member hardened by reason of the local compacting of the grain, while at the same time decreasing the overall width of said end portion and increasing the overall thickness appreciably above that of the original bar, and finally drilling a pintle hole crosswise in said thickened end portion.

SETH B. ATWOOD.
